ADAPTER FOR A CIRCUIT BREAKER

Ralph B. Davis, Lawrence Township, Mercer County, N.J., assignor to Heinemann Electric Company, Trenton, N.J.

Filed Dec. 2, 1969, Ser. No. 20,330

Term of patent 14 years

Int. Cl. D13—03

U.S. Cl. D26—13

Fig. 2

Fig. 3

Fig. 4

FIG. 1 is a front perspective view of an adapter for a circuit breaker showing my new design;

FIG. 2 is a front elevational view thereof;

FIG. 3 is a side elevational view thereof; and

FIG. 4 is a bottom plan view thereof.

The portions of the figures shown in broken lines are shown for illustrative purposes only.

I claim:

The ornamental design of an adapter for a circuit breaker, as shown and described.
